(57) **CLAIM**

The ornamental design for a combined toilet cleaning brush with T-shaped handle and holder therefor, as shown and described.

DESCRIPTION

FIG. 1 is a front, side, and top perspective view of a combined toilet cleaning brush with T-shaped handle and holder therefor showing my new design;

FIG. 2 is a front, side, and top perspective view of the toilet cleaning brush of FIG. 1, shown separately for clarity of illustration only;

FIG. 3 is an enlarged side elevation view of the design as shown in FIG. 2;

FIG. 4 is an elevation view of the opposite side of the design as shown in FIG. 3;

FIG. 5 is a front elevation view of the design as shown in FIG. 3;

FIG. 6 is a rear elevation view of the design as shown in FIG. 3;

FIG. 7 is a top plan view of the design as shown in FIG. 3;

FIG. 8 is a bottom plan view of the design as shown in FIG. 3; FIG. 9 is an enlarged side elevation view of the design as shown in FIG. 1;

FIG. 10 is an elevation view of the opposite side of the design as shown in FIG. 9;

FIG. 11 is a front elevation view of the design as shown in FIG. 9;

FIG. 12 is a rear elevation view of the design as shown in FIG. 9;

FIG. 13 is a top plan view of the design as shown in FIG. 9; and,

FIG. 14 is a bottom plan view of the design as shown in FIG. 9.
